COMBINED ASH TRAY STAND AND RECEPTACLE

John Sherwood, Cumberland, Md.

Application June 3, 1957, Serial No. 46,456

Term of patent 14 years

(Cl. D85—2)

Fig. 1 is an elevational view of a combined ash tray stand and receptacle, showing my new design;

Fig. 2 is a top plan view; and

Fig. 3 is a vertical sectional view taken on line 3—3 of Fig. 2.

I claim:

The ornamental design for a combined ash tray stand and receptacle, as shown.
